CLAIM

The ornamental design for a waist pack, as shown and described.

DESCRIPTION

FIG. 1 is a front perspective view of a waist pack, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof;

FIG. 11 is an enlarged detail view of area 11 in FIG. 2 thereof;

FIG. 12 is an enlarged detail view of area 12 in FIG. 5 thereof; and,

FIG. 13 is an enlarged detail view of area 13 in FIG. 7. The dash-dot-dash broken lines in FIGS. 1, 2, 5 and 7 depict the bounds of the enlargement taken from FIGS. 1, 2, 5 and 7 and form no part of the claimed design.

1 Claim, 13 Drawing Sheets
